Primary Examiner — Marianne Pandozzi(74) Attorney, Agent, or Firm — Curtis L. Harrington; Harrington & Harrington(57) CLAIM

The ornamental design for a mug, as shown and described.

DESCRIPTION

FIG. 1 is a front perspective view of the mug;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines in the drawings are included for the purpose of illustration and form no part of the claimed design.
